DRIVE FOR HOME RECORDERS

Ingo L. Stephan, Delanco, N. J., assignor to Philco Radio and Television Corporation, Philadelphia, Pa., a corporation of Delaware

Application January 7, 1942, Serial No. 425,934

29 Claims. (Cl. 274—13)

This invention relates to recording apparatus for phonographs, and more especially to means for controlling the recording stylus of the apparatus while cutting a sound groove in a blank record, and while the phonograph is being used for normal reproducing purposes.

Prior to the present invention, recording devices for phonographs were of a complex, expensive construction requiring critical adjustment and operation by one highly skilled in the technique of recording.

The current popularity of home recording has created a demand for a recording apparatus of a more simple construction capable of being installed, adjusted and successfully operated by an ordinary individual having no particular mechanical aptitude or experience in the art of recording.

The principal object of the invention is to provide a simple, efficient mechanism for driving the recording stylus in an arcuate path across the face of a blank record disc positioned on and being rotated by the revolving turntable of the phonograph, for cutting a conventional continuous spiral sound groove in the record disc.

Another object of the invention is to provide simple, efficient means for releasing the stylus-driving means from its primary actuating means and for locking the stylus and its driving means out of action during normal operation of the phonograph for reproducing purposes.

The construction and operation of the driving means and lock-out means forming the subject matter of the present invention, together with immediately associated mechanism of a conventional phonograph, will be fully disclosed hereinafter, reference being had to the accompanying drawings, of which:

Fig. 1 is a vertical elevation, with certain parts shown in section, of a recording device constructed in accordance with this invention and applied to a conventional phonograph device;

Fig. 2 is a perspective view looking upwardly at the under side of the driving and lock-out unit for the recording stylus;

Figs. 3 and 4 are detached perspective views of various parts of the assembled device shown in Fig. 2; and

Fig. 5 is an enlarged sectional view illustrating a detail of the invention.

Referring to the drawings, there is shown in Fig. 1 a portion of a conventional phonograph comprising a base member 10 having a turntable 11 mounted thereon for rotation at a uniform

speed, by a motor (not shown), during operation of the recorder. Removably mounted on the turntable 11 is a blank record disc D which is arranged to be rotated by and with the turntable.

In accordance with conventional practice, a recording unit comprising a pivoted stylus carrying arm 13, which supports an electro-acoustic transducer or "cartridge" element 14, are provided. The cartridge 14 carries the cutting stylus 15. The recording stylus 15 is adapted to cut a swarf from the disc D. The arm 13 is arranged for horizontal swinging movement about a vertical axis, by virtue of a bearing post 16 through which a stud shaft 17 extends, and in which said shaft is rotatably mounted. The arm 13 is pivotally mounted for free rocking movement in a vertical plane on a collar 18 which is rigidly secured to the upper end of the shaft 17. A driving arm 19 is rigidly secured to the lower end of shaft 17, for rotation in synchronism with movement of the arm 13. Thus, any swinging movement of the driving arm 19 about the axis of the shaft 17 in its pivotal mounting 16 will cause a corresponding swinging movement of the stylus-supporting arm 13 over the face of disc D. Thus, if the arms 19 and 13 are advanced at a generally uniform rate, the stylus 15 will cut a continuous spiral sound groove in the upper face of disc D.

It will be understood that if an electrical signal is applied to the cartridge 14, the stylus 15 will be caused to oscillate laterally, in addition to its general groove-cutting motion by the arm 13, in a manner to cause audio frequency undulations to be formed in the sound groove.

Considering now the means for rotating the driving arm 19, as shown in Figs. 2, 3, and 4, a sub-base 20 is provided for supporting certain elements of the driving unit. The sub-base 20 is supported, with respect to base 10, by the post 16 and by one or more relatively spaced screw fastenings 21. Pivotally secured at 22 to the sub-base 20, is a swing plate 23 which has an outwardly-extending finger 24. A spring 25, connected between the finger 24 and the sub-base 20, tends to rotate the swing plate 23 clockwise (as seen in Fig. 2) about its pivot 22.

On the swing plate 23, there is a pivot stud 26, which carries a hub member 27 (see Fig. 4). At its inner end the hub 27 is fixed to a ratchet wheel 28. To the upper face of the ratchet wheel 28 is affixed a cork disc 29. Between the disc 29 and the swing plate 23, there is provided

a unilateral clutch plate 30, which will be described hereinafter.

Loosely mounted, for free rotation, on an annular stepped portion of the hub 27, between one of the steps of said hub and the ratchet wheel 28, is an actuating lever 31, which is provided with a vertically-offset portion 32 extending up through an opening in base plate 10 (see Fig. 1). The free end of the lever 31 is provided with a cam follower, in the form of a roller 33 which bears against an edge cam 34.

The cam 34 is preferably formed on or secured to the central hub of the turntable 11, so as to rotate therewith. As shown in Fig. 2, the cam 34 may be merely a circular disc arranged eccentrically of the axis of rotation of the turntable.

On that side of the lever 31, opposite the driving lever 32, is pivoted a driving pawl 35, which is biased by a spring 36 into engagement with the teeth of the ratchet wheel 28. A spring 37 operating between the lever 31 and the swing plate 23 serves to maintain the cam follower 33 in continuous engagement with the cam 34 during operation of the device.

By reason of the above construction, the actuating lever 31 will oscillate freely about the hub 27, in timed relation to the rotation of the turntable 11, causing the pawl 35 to rotate the ratchet wheel 28 and consequently the hub 27 step by step in one direction. If the cam 34 is an eccentrically-mounted circular disc, as shown, the ratchet mechanism will advance the hub 27 during substantially one half of each revolution of the turntable 11, and during the remaining half revolution, the unilateral clutch plate 30 will engage the cork disc 29 and prevent retrograde movement of the ratchet wheel 28 and hub 27.

As shown in Fig. 3, the clutch plate 30 comprises a thin metal plate having numerous resilient teeth or serrations 38, which are cut in the clutch plate 30 and bent outwardly from the plane thereof at an angle thereto. These serrations are inclined, as shown, to permit free forward rotation of ratchet wheel 28, by the pawl 35, but any tendency for rearward movement of the ratchet wheel will be prevented by the serrations biting into the adjacent face of cork disc 29, which is secured to the ratchet wheel 28.

Further in accordance with this construction, the hub 27 is provided with a V shaped circumferential groove 39. The lower flange forming one of the convergent side walls of the groove 39, has been removed in Fig. 2 so as to show more clearly the operation of the mechanism. The driving arm 19 terminates in an arcuate portion 40 having an outer arcuate edge, concentric to the axis of the stud shaft 17, and which, as shown in Fig. 5, contacts beveled surfaces 39a and 39b of the groove 39 (Figs. 1 and 2). The upper and lower edges 40a and 40b of the sector portion 40 are suitably chamfered to make a tight surface-to-surface contact between the sector member 40 and the grooved hub 27, under pressure of the spring 25. This wedging driving engagement between said edges and the converging side walls of the V-shaped groove obviates the possibility of slippage and insures that oscillation of the actuating lever 31, and consequent intermittent rotation of the hub 27, will effect intermittent rotation of the driving arm 19, the shaft 17, and the stylus-supporting arm 13. Accordingly, the stylus 15 will be moved across the face of record D in a manner to cut a generally spiral sound groove therein.

In apparatus of the above type it is most de-

sirable to mount the drive means permanently in association with the phonograph and under such circumstances it is necessary to provide a form of "lock-out" to prevent operation of the drive for the recording mechanism during use of the turntable for normal reproducing operation of the phonograph. To this end, the actuating lever 31 is provided with a pin or lug 41, and the outer end or tip portion 42 of the segmental extension of the driving arm 19 is provided with a pair of notches 43 and 44. These parts are so arranged that when the stylus-supporting arm 13 has been swung clockwise to an extreme outer or off position, clear of the turntable 11, the driving arm 19 will likewise be in its extreme off position. In such position of the segment 40, the pin or other abutment 41 will be located in the indexing notch 43, while the clearance notch 44 will lie adjacent the groove 39 of the driving pinion portion of the hub 27. However, the notch 44 is sufficiently deep to prevent engagement of the outer edge of the segment 40 with the convergent side walls of the groove 39. Moreover, when the driving arm 19 and its segmental end 40, are swung to the off position, a cam surface 47 on the outer edge of the segment 40, between the clearance notch 44 and the indexing or lock-out notch 43, engages the lock-out pin 41 and swings the actuating arm 31 about its pivot 26 until the cam follower 33 is clear of the actuating cam 34 on the turntable 11. Accordingly, during use of the turntable 11 in normal reproducing operation of the phonograph there will be no transmission of motion to the stylus arm 13, etc., through the drive mechanism.

Upon movement of the stylus arm 13 and driving arm 19, as when the stylus 15 is manually placed on and adjacent the outer edge of a record D, the indexing notch 43 will move laterally away from pin 41 thereby releasing the driving means and the stylus from the lock-out means and the drive will again become operative to move the stylus arm 13 across the face of the record D. After the recording has been made, the stylus arm 13 will be raised and manually swung to its off position, which, in the present instance, is clear of the grooved face of the record, simultaneously returning the driving arm 19 to the starting position shown in Fig. 2.

If desired, a phonograph-recording changeover switch 45 may be provided. As shown in Fig. 2, the switch 45 may conveniently be actuated automatically by the driving arm 19 when in its off position.

The swing plate 23 is provided with a shouldered pin 51 which passes through and operates in a slot 52 formed in the sub-base 20 to stabilize the swing plate 23 and the rotary elements of the driving unit carried thereby as the spring 25 moves the plate 23 about its pivot to effect firm driving contact between the chamfered edge of the segment 40 and the driving pinion formed by the groove 39 in the hub 27.

As shown in Fig. 1, the pivot stud 26 carrying hub 27, clutch disc 30, and ratchet wheel 28, is provided, beyond the lower end of the hub 27, with a washer 53 and lock nuts 54, 54. Between the washer 53 and the lower end of the hub 27 is a spring 55 which maintains the hub 27 with the ratchet wheel 28 thereon and the clutch discs 29 and 30 in firm but yielding axial relationship to each other to permit proper operation of the clutch during retrograde oscillation of the actuating lever 31.

It will be clear from the above described construction that I have provided a novel, simple,

and efficient drive and lock-out mechanism for recording apparatus, but my invention as above described may be modified and should be considered limited only by the following claims.

For assembly purposes, the actuating lever 31 is provided with a slot 50 and the swing plate 23 is provided with a projection 46 which extends into the slot 50, the opposite ends 48 and 49 of which hold the lever 31, and parts associated therewith, within certain limits prior to the driving unit shown in Fig. 2 being installed on the phonograph.

I claim:

1. In a recording apparatus employing a stylus for cutting a sound groove in a rotating phonograph record, a stylus-supporting arm mounted for pivotal movement parallel to the face to the record, a driving arm connected to and adapted for pivotal movement concurrently with said stylus-supporting arm, a rotatable member engageable directly with said driving arm, and power transmitting means including rotary input and output elements and intermediate reciprocating mechanism operable periodically to impart intermittent uni-directional rotary motion to said rotatable member in predetermined relation to the rotations of said record for effecting traverse of the stylus across the face of the record.

2. In a recording apparatus employing a stylus for cutting a sound groove in a rotating phonograph record, a stylus-supporting arm operable parallel to the face of the record, a driving arm and having an arcuate edge disposed beneath the record and connected to said stylus-supporting arm and having an arcuate edge movable in a predetermined plane, a driving member rotatable about an axis substantially perpendicular to the plane in which said edge of said driving arm moves and frictionally engageable with said edge, and means for rotating said member in predetermined relation to the rotations of said record for effecting traverse of the stylus across the face of the record.

3. In a recording apparatus employing a stylus for cutting a sound groove in a rotating phonograph record, a stylus-supporting arm operable parallel to the face of the record, a driving arm connected to said stylus-supporting arm and having an arcuate edge movable in a predetermined plane, a driving member rotatable about an axis substantially perpendicular to the plane in which said edge of said driving arm moves and frictionally engageable with said driving arm, movable means supporting said driving member, resilient control means for said movable supporting means and affording relative lateral movement between said driving arm and said driving member to effect firm frictional driving engagement between said driving member and said driving arm, and means carried by said movable support for rotating said driving member in predetermined relation to the rotations of said record for effecting traverse of the stylus across the face of the record.

4. In a recording apparatus employing a stylus for cutting a sound groove in a rotating phonograph record, a stylus-supporting arm operable parallel to the face of the record, a driving arm connected to said stylus-supporting arm and having an arcuate edge movable in a predetermined plane, a driving member rotatable about an axis substantially perpendicular to the plane in which said edge of said driving arm moves and frictionally engageable with said driving

arm, movable means supporting said member, resilient means for moving said support to effect firm frictional engagement between said arm and said member, primary actuating means rotatable with said record, and means carried by said movable support and operable by said primary actuating means for rotating said member in predetermined relation to the rotations of said record for effecting traverse of the stylus across the face of the record.

5. In a recording apparatus employing a stylus for cutting a sound groove in a rotating phonograph record, a stylus-supporting arm operable parallel to the face of the record, a driving arm connected to said stylus-supporting arm and having an arcuate edge, a driving member rotatable about an axis substantially perpendicular to the plane in which said edge of said driving arm moves and frictionally engageable with said edge, resilient means urging said member into firm frictional driving engagement with said edge, and means for rotating said member to effect traverse of the stylus across the face of the record.

6. In a recording apparatus employing a stylus for cutting a sound groove in a rotating phonograph record, a stylus-supporting arm operable parallel to the face of the record, a driving arm connected to said stylus-supporting arm, a segmental extension on said driving arm and having an arcuate edge, a driving member, means supporting said member with its axis of rotation substantially perpendicular to the plane of said driving arm and urging it resiliently into firm frictional driving engagement with said edge, primary actuating means rotatable with said record, and means carried by said member supporting means and operable by said primary actuating means for rotating said driving member to effect traverse of the stylus across the face of the record.

7. In a recording apparatus employing a stylus for cutting a sound groove in a rotating phonograph record, a stylus-supporting arm operable parallel to the face of the record, a driving arm connected to said stylus-supporting arm, a driving member engageable with said driving arm, means for rotating said member to effect traverse of the stylus across the face of the record including a ratchet wheel drivingly-connected to said member, an actuating lever freely rockable with respect to the ratchet wheel, a pawl pivoted to said lever and engageable with said ratchet wheel, and means for rocking said lever to rotate said member.

8. In a recording apparatus employing a stylus for cutting a sound groove in a rotating phonograph record, a stylus-supporting arm operable parallel to the face of the record, a driving arm connected to said stylus-supporting arm and having an arcuate edge, a driving member frictionally engageable with said edge, and means for rotating said member in predetermined relation to the rotations of said record for effecting traverse of the stylus across the face of the record, including a ratchet wheel drivingly-connected to said member, an actuating lever, a pawl pivoted to said lever and engageable with said ratchet wheel, and cam means rotatable with said record for rocking said lever.

9. In a recording apparatus employing a stylus for cutting a sound groove in a rotating phonograph record, a stylus-supporting arm operable parallel to the face of the record, a driving arm connected to said stylus-supporting arm and having an arcuate edge, a driving member

ally engageable with said edge, resilient means supporting said member to effect firm frictional driving engagement between said member and said driving arm, and means for rotating said member comprising a ratchet wheel carried by said resilient means and drivingly connected to said member, an actuating lever carried by said resilient means, a pawl pivoted to said lever and engageable with said ratchet wheel, and cam means for rocking said lever in timed relation to the rotations of said record.

10. In a recording apparatus employing a stylus for cutting a sound groove in a rotating phonograph record, a stylus-supporting arm operable parallel to the face of the record, a driving arm connected to said stylus-supporting arm, a segmental extension on the outer end of said driving arm having an arcuate edge, a driving pinion frictionally engageable with said arcuate edge of the segmental extension of said driving arm, resilient means supporting said pinion to effect firm frictional driving engagement between said pinion and said driving arm, a ratchet wheel drivingly connected to said pinion, an actuating lever, a pawl pivoted to said lever and engageable with said ratchet wheel, a cam follower on said lever, and an eccentric cam rotatable with said record for oscillating said lever to effect traverse of the stylus across the face of the record.

11. In a recording apparatus employing a stylus for cutting a sound groove in a rotating phonograph record, a base structure, a stylus-supporting arm pivotally mounted on said base, a driving arm connected to said stylus-supporting arm for swinging movement therewith, a swing plate pivoted to said base structure, a driving member rotatably mounted in said swing plate with its axis of rotation substantially perpendicular to the plane of said driving arm and disposed for frictional driving engagement with said driving arm, means resiliently swinging said plate to effect said frictional driving engagement, and means carried by said swing plate for rotating said driving member.

12. In a recording apparatus employing a stylus for cutting a sound groove in a rotating phonograph record, a base structure, a stylus-supporting arm pivotally mounted on said base structure, a driving arm connected to said stylus-supporting arm for swinging movement therewith, a swing plate pivoted to said base structure, a pinion rotatably mounted in said swing plate for frictional driving engagement with an arcuate edge of said driving arm, means resiliently swinging said plate to effect said frictional driving engagement, an actuating lever mounted on said swing plate for oscillation about the axis of said pinion, a ratchet wheel drivingly connected to said pinion, a pawl pivoted on said actuating lever and engageable with said ratchet wheel, an actuating cam rotatable with said record, and a cam follower on said actuating lever engageable by said cam for intermittently rotating said pinion.

13. In a recording apparatus employing a stylus for cutting a sound groove in a rotating phonograph record, a pivotally mounted stylus-supporting arm, a driving arm connected to said stylus-supporting arm for swinging movement therewith, a rotary pinion for operating said driving arm, an oscillatory lever for turning said pinion, a ratchet wheel drivingly connected to said pinion, a pawl on said lever and engageable with said ratchet wheel, means for rocking said lever to rotate said ratchet wheel and said pinion intermittently, a rotary clutch member connected

10 to said ratchet wheel for rotation therewith, and a stationary clutch member for cooperation with said rotary clutch member to prevent retrograde motion of said ratchet wheel and pinion.

14. In a recording apparatus employing a stylus for cutting a sound groove in a rotating record, a recording arm mounted for movement across the face of the record, an arcuate sector member drivingly connected to said arm, rotatable drive means in engagement with said sector member, an eccentric drive member, and means comprising a lever oscillatable by said eccentric drive member, and having a driving and a return stroke, said last means being constructed and arranged to actuate said rotatable drive means during the driving stroke and thereby effect intermittent advance of said sector member with respect to said drive means.

15. In a recording apparatus employing a stylus for cutting a sound groove in a rotating phonograph record, a stylus-supporting arm operable parallel to the face of the record, a second arm drivingly connected to said stylus-supporting arm and having a chamfered arcuate edge, a driving pinion having a circumferential groove with converging side walls formed therein, means maintaining said side walls in wedging contact with the chamfered edges of said driving arm, and means for rotating said pinion in predetermined relation to the rotations of said record for effecting traverse of the stylus across the face of the record.

16. In a recording apparatus employing a stylus for cutting a sound groove in a rotating phonograph record, a stylus-supporting arm operable parallel to the face of the record, a driving arm connected to said stylus-supporting arm, a driving member engageable with said driving arm, means actuating said driving member in predetermined relation to the rotations of said record for effecting traverse of the stylus across the face of the record, and means operable by said driving arm for moving said driving member from and locking said driving member out of driving contact with said driving arm.

17. In a recording apparatus employing a stylus for cutting a sound groove in a rotating phonograph record, a stylus-supporting arm operable parallel to the face of the record, a driving arm connected to said stylus-supporting arm, a driving member engageable with said driving arm, primary actuating means rotatable with said record, complementary means operated by said primary means for rotating said member to effect traverse of the stylus across the face of the record, and cooperating means carried by said driving arm and said complementary means respectively for locking said complementary means out of engagement with said primary actuating means when said stylus is moved to a position of rest with respect to said record.

18. In a recording apparatus employing a stylus for cutting a sound groove in a rotating phonograph record, a stylus-supporting arm operable parallel to the face of the record, means for effecting traverse of said stylus across the face of the record by its supporting arm comprising a driving arm connected to said stylus-supporting arm and having an arcuate edge movable in a predetermined plane, a driving member rotatable about an axis substantially perpendicular to the plane in which said edge of said driving arm moves and engageable with said driving arm, means actuating said driving member in predetermined relation to the rotations of said record,

and means responsive to said parallel movement of said stylus-supporting arm from an operative position to a position of rest and adapted to disengage said driving member from said edge of the driving arm for stopping actuation of said driving arm by said actuating means.

19. In a recording apparatus employing a stylus for cutting a sound groove in a rotating phonograph record, a stylus-supporting arm operable parallel to the face of the record, a driving arm connected to said stylus-supporting arm, a driving member engageable with said driving arm, primary actuating means rotatable with said record, means operable by said primary actuating means for actuating said member to effect traverse of the stylus across the face of the record, and means responsive to movement of said stylus-supporting arm from an operative to a rest position for disengaging said driving member from said primary actuating means.

20. In a recording apparatus employing a stylus for cutting a sound groove in a rotating phonograph record, a stylus-supporting arm operable parallel to the face of the record, a driving arm connected to said stylus-supporting arm and having an arcuate edge movable in a predetermined plane, a driving member rotatable about an axis substantially perpendicular to the plane in which said edge of said driving arm moves and engageable with said driving arm, a movable support for said driving member, primary actuating means rotatable with said record, means operable by said primary actuating means for actuating said driving member to effect traverse of the stylus across the face of the record through said driving arm, and means responsive to said parallel movement of said stylus-supporting arm from an operative to a rest position and adapted to actuate said support for disengaging said driving member from said driving arm.

21. In a recording apparatus employing a stylus for cutting a sound groove in a rotating phonograph record, a stylus-supporting arm operable parallel to the face of the record, a driving arm connected to said stylus-supporting arm, a driving member engageable with said driving arm, primary actuating means rotatable with said record, complementary means operated by said primary means for rotating said member to effect traverse of the stylus across the face of the record, and means for removing said complementary means from operative engagement with said primary actuating means when said stylus is moved to a position of rest with respect to said record.

22. In a recording apparatus employing a stylus for cutting a sound groove in a rotating phonograph record, a stylus-supporting arm operable parallel to the face of the record, an arm in driving relation to said stylus-supporting arm, a driving member engageable with said driving arm, ratchet means for rotating said member to effect traverse of the stylus across the face of the record comprising an actuating lever, a cam follower on said lever, an eccentric cam rotatable with said record for oscillating said lever, an index notch on said lever, and an abutment on said lever, and an index notch on said driving arm engageable with said abutment to hold said cam follower out of contact with said cam when the stylus-supporting arm is moved from an operative to a rest position with respect to said record.

23. In a recording apparatus employing a stylus for cutting a sound groove in a rotating phonograph record, a stylus-supporting arm operable

parallel to the face of the record, a driving arm connected to said stylus-supporting arm, a driving pinion engageable with said driving arm, ratchet means for rotating said pinion to effect traverse of the stylus across the face of the record, an actuating lever for operating said ratchet means, a cam follower on said lever, an eccentric cam rotatable with said record for oscillating said lever, a pin on said lever, an index notch on said driving arm engageable with said pin to hold said cam follower out of contact with said cam when the stylus-supporting arm is moved from an operative to a rest position with respect to said record.

15. 24. In a recording apparatus employing a stylus for cutting a sound groove in a rotating phonograph record, a stylus-supporting arm operable parallel to the face of the record, a driving arm connected to said stylus-supporting arm and having a plain arcuate edge, a driving pinion frictionally engageable with said arcuate edge, a resilient mounting for said pinion to effect firm frictional driving engagement between said pinion and said driving arm, means for rotating said pinion to effect traverse of the stylus across the face of the record comprising an actuating lever, a cam follower on said lever, an eccentric cam rotatable with said record for oscillating said lever, a pin on said lever, an index notch on said driving arm engageable with said pin to hold said cam follower out of contact with said cam when the stylus is moved to a position of rest, and a clearance notch on said edge of said driving arm adjacent said pinion to release said pinion from said frictional driving engagement with said driving arm.

25. 25. In a recording apparatus employing a stylus for cutting a sound groove in a rotating phonograph record, a stylus-supporting arm operable parallel to the face of the record, a driving arm element connected to said stylus-supporting arm, a driving pinion frictionally engageable with said driving arm, a movable supporting element for said pinion, means for rotating said pinion to effect traverse of the stylus across the face of the record, a pin on one of said elements and a cam on the other of said elements for effecting disengagement between said pinion and said driving arm when said stylus-supporting arm is moved from an operative to a rest position relative to said record.

40. 26. A control unit for a groove cutting stylus engaging a rotating record in a phonographic recorder having a driving element for effecting lateral progression of the stylus across the record, said unit comprising a rotary element engageable with said driving element, a reciprocable impulse element operable in synchronization with the rotations of the record, and an intermediate element intermittently operable by said impulse element and operatively connected to said rotary element to impart intermittent rotation thereto and consequent step by step progression to said stylus through said driving element.

55. 27. A control unit for a groove cutting stylus engaging a rotating record in a phonographic recorder having a driving element for effecting lateral progression of the stylus across the record, said unit comprising a swing frame, a rotary element carried by said swing frame and engageable with said driving element, a reciprocable impulse element carried by said swing frame and operable in synchronization with the rotations of the record, and an intermediate element carried by said swing frame and intermittently operable by said

impulse element and operatively connected to said rotary element to impart intermittent rotation thereto and consequent step by step progression to said stylus through said driving element.

28. A control unit for a groove cutting stylus engaging a rotating record in a phonographic recorder having a driving element for effecting lateral progression of the stylus across the record, said unit comprising a swing frame, a shaft rotatably mounted in said swing frame, a rotary element secured to said shaft and engageable with said driving element, a reciprocable impulse element carried by said swing frame and operable in synchronization with the rotations of the record, and an intermediate element secured to said shaft and intermittently operable by said impulse element and operatively connected to said rotary element to impart intermittent rotation thereto and consequent step by step progression to said stylus through said driving element.

29. A control unit for a groove cutting stylus

engaging a rotating record in a phonographic recorder having a driving element for effecting lateral progression of the stylus across the record, said unit comprising a swing frame, a shaft rotatably mounted in said swing frame, a rotary element secured to said shaft and engageable with said driving element, a reciprocable impulse element carried by said swing frame and operable in synchronization with the rotations of the record, an intermediate element secured to said shaft and intermittently operable by said impulse element and operatively connected to said rotary element to impart intermittent rotation thereto and consequent step by step progression to said stylus through said driving element, and anti-retrogressive means anchored to said frame and engageable with one of said elements on said shaft to prevent retrogression of said rotary element.

INGO L. STEPHAN.
